J. H. Mann,
Harvester Cutter.

No. 14544

Patented. Mar. 25, 1858

FIGURE 1.

FIG. 2.

UNITED STATES PATENT OFFICE.

JOHN H. MANNY, OF ROCKFORD, ILLINOIS, ASSIGNOR TO PETER H. WATSON.

IMPROVEMENT IN HARVESTER-CUTTERS.

Specification forming part of Letters Patent No. 14,544, dated March 25, 1856.

To all whom it may concern:

Be it known that I, JOHN H. MANNY, of Rockford, in the county of Winnebago and State of Illinois, have invented a new and useful Sickle for Harvesting-Machines, which I denominate the "Reversible Duplex Sickle," of which the following is a full, clear, and exact description, reference being had to the accompanying drawings, which make part of this specification, and in which—

Figure 1 is a plan of a sickle embracing my improvement, one edge being serrated and the other smooth. Fig. 2 represents a view of the same turned bottom side uppermost.

My invention and improvement consists in constructing a sickle with two edges in such manner that either of them may at will be presented toward the front of the machine to cut grain or grass, so that in case one edge becomes dull or injured the other may be brought into use, or if one edge is serrated and the other smooth, one scalloped and the other straight, or if they are otherwise diversified, that edge which is best adapted for any particular circumstance or occasion ought to be used.

The accompanying drawings represent a sickle or cutter composed of a bar or stock, *a*, to which a series of quadrilateral plates, *b*, are secured by rivets or screws, which plates have their four edges sharpened, two adjacent edges being plain and the other two serrated. These plates are secured to the bar in such manner that the corner at which the two plain edges meet will project on one side of the bar, and the opposite corner at which the two serrated edges meet will project on the opposite side of the bar, the two corners at which the plain and serrated edges meet being on a line parallel to the edge of the stock. At each end of the series of plates a clearing-hook, *c*, is secured to the stock *a*, the hooks being bent inward, so that when they enter the guides or bearings in the guards or dividers they will tend to push the stalks of grass or other fiber aside instead of pushing it directly into the opening in the guard, and when they are withdrawn from the opening they will tend to hook and draw out any fibers that may have been forced in. Thus

the action of the hooks will be such as to prevent an accumulation of fiber in the guides in which these hooks and the extremities of the sickle play that would cause great friction or endanger clogging.

The stock of the sickle, unlike others heretofore known, has an eye, *d*, at each end to connect with the connecting-rod by which it is vibrated. By this means the two ends of the sickle may be reversed in position to turn either edge of the sickle foremost, as may be desired.

If the sickle were constructed either without a stock or with the stock projecting equally on both sides of the plates, instead of on one side only, as shown in the example represented in the drawings, then the edges of the sickle could be reversed by simply turning it over, and without reversing its ends.

The sickle-blade can be made of a single piece, or of any number of pieces less than that shown in the drawings, or it may be varied otherwise, as my invention relates to the reversibility of a two-edged sickle and not to its form, construction, or operation in other respects.

Among the advantages of this kind of sickle may be mentioned its superior durability, for having two edges to wear they will necessarily last longer than one edge would. Further, that as one edge may be serrated and more especially adapted to cutting grain and the other smooth and better adapted to cutting grass, the same sickle will answer for both reaping and mowing, whereas heretofore it required a separate sickle for each of these purposes, and I have always supplied machines with two.

What I claim as my invention, and desire to secure by Letters Patent, is—

The reversible duplex sickle, substantially as herein described.

In testimony whereof I have hereunto subscribed my name.

JOHN H. MANNY.

In presence of—

JESSE BLIME,
NEWTON CRAWFORD.
